WATER-TUBE BOILER.

1,106,453.

Specification of Letters Patent. Patented Aug. 11, 1914.

Application filed July 16, 1912. Serial No. 709,770.

To all whom it may concern:

Be it known that I, DAVID S. JACOBUS, a citizen of the United States, residing at Jersey City, in the county of Hudson and State 5 of New Jersey, have invented certain new and useful Improvements in Water-Tube Boilers, of which the following is a specification.

My invention relates to a water tube boiler 10 and more particularly to a means for admitting air at the center of the fuel chamber in a type of boiler having an A-shaped combustion chamber of relatively large volume, although it is not limited to the use of 15 such a furnace.

In the particular application of my invention illustrated in the accompanying drawings, the combustion chamber extends beneath the entire boiler and is fired from both 20 the front and rear, the purpose being to supply air for combustion to the unconsumed carbon lying adjacent to the side walls of a division wall extending transversely of the fuel chamber.

25 In the drawings Figure 1 is a longitudinal section through a boiler of the type referred to, showing one application of my invention; and Fig. 2 is a section illustrating a modification of the division wall.

30 Similar reference numerals indicate similar parts in the two views.

The particular boiler selected for the purpose of illustrating my invention, is a type comprising units symmetrically disposed 35 over a common combustion chamber and forming between them an A-shaped combustion chamber of relatively large volume. In recent tests with a boiler of this type, combining large furnace volume with the particular form and height of furnace, the width of the furnace from one side to the other of the boiler being about 26 $\frac{1}{2}$ feet, the depth from the front to the rear of the boiler about 14 feet, and the height, measured 40 above the dumping plates to the top of the first baffle, about 29 feet, it was found that the admission of air, in the manner herein described, led to better efficiencies with certain grades of coal than were secured without it.

Sufficient parts of the boiler are shown for the present purpose. It comprises two units each consisting of two banks of tubes, the left hand unit having front and rear

banks 1 and 2, and the right hand unit, front 55 and rear banks 3 and 4. The tubes of the left hand unit are expanded into a water drum 5 and those of the right hand unit into a water drum 6, the said drums being located above the furnace arches 7 and 8. The upper ends of the tubes of banks 1 and 3 are expanded into a middle steam and water drum 9; the tubes 2 into a drum 10, and the tubes 4 into a drum 11, the steam spaces of said drums being connected by pipes 12 and 60 their water spaces by pipes 13. All of these drums extend transversely of the setting. Baffles 14 and 15 extend upwardly from the drums 5 and 6 and are supported upon the back row of tubes of banks 1 and 3 respectively. Additional baffles 16 and 17 extend downwardly from the roof to properly direct the course of the gases along the tubes to the two outlet flues 26 and 27. Superheaters 18 and 19 are supported in the spaces 70 forming the downward passes of the gases between the sets of baffles.

The fuel chamber extends beneath the entire boiler and comprises two inclined stokers, one at the front and the other at the 80 rear of the boiler, each stoker having a dumping plate at the bottom. In the drawings I have shown only the supports 20 and 21 for the stoker grate bars and the supports to which the dumping plates are hinged. A 85 low division wall 22 extends transversely of the furnace between the two stokers, the dumping plates being adjacent the side walls of the division wall 22.

In the operation of stokers of the type described, the ash is gotten rid of by dumping it at times from the dumping plates, but in the use of such plates there is usually considerable loss through unconsumed combustible matter in the ash, and the purpose of 90 the present invention is to burn the combustible matter out of the coke or partly spent coal lying on the dumping plates, as well as to supply air at the middle of the furnace, by admitting air above the coke or 100 partly spent coal through openings in the division wall 22 and, directing the air downward on top of and across this material so as to burn the combustible matter from the top part of the bed of partly spent coal lying 105 on the dumping plate. For that purpose the wall is made hollow, or with a suitable duct, and the side walls formed with a se-

ries of openings 23 leading from the central duct into the furnace chamber about or a little above the material lying on the dumping plates; or the openings 23 may be left in the brick work. As a preferred construction I run a pipe 24 through the division wall, said pipe being formed with openings which will register with the openings 23. The openings 23 are set at such a height that the air supplied through them will blow over and impinge on the top of the partly spent coal and clinkers lying on the dumping plates adjacent to the side walls, and thus supply the necessary oxygen for burning out the unconsumed combustible matter. Additionally, a certain amount of air along the middle of the furnace has been found to increase the economy under certain operating conditions by burning the combustible gases distilled from the coal.

The openings 23 may be inclined downward, but in the form shown in Fig. 1 it has been found in practice that the slag which runs down the faces of the wall 22 forms a hood over the openings and causes the air to be deflected downward in the way intended. In order however to simplify the construction the openings were made horizontal.

It is preferred to supply the air under pressure and for that purpose the pipe 24 may be connected to any suitable source of supply, valves or other devices in the pipe being employed to regulate the amount of air and its pressure.

By the use of a supplementary supply of air playing downward upon and across the fire on the dumping plate of a stoker for burning out the combustible from the ash which collects on the dumping plate, it is possible to keep the fire on the plate at a predetermined thickness without reference to the thickness on the main part of the grate.

In Fig. 2 a slight modification is shown in which the sides of the division wall are provided with water boxes 25 and 26, the air openings between the boxes being inclined downward. In this construction the air is supplied through a duct in the division wall.

What I claim is:

1. In combination, a steam boiler, a furnace therefor, a bridge wall having openings therein, and means for admitting air through said openings so as to make it im-

pinge on the top of the fire adjacent the bridge wall for the purpose described.

2. In combination, a steam boiler, a stoker having at its rear a dumping plate, 60 and a bridge wall, said bridge wall having air openings so arranged as to direct the incoming air downward on top of and across the surface of the fire on the dumping plate. 65

3. In combination, a steam boiler, a furnace therefor, a dumping plate at the rear of the furnace and adjacent a bridge wall, said bridge wall having openings therein, and means for admitting air through said 70 openings so as to make the air impinge on the top of the fire carried by the dumping plate for the purpose of burning the combustible elements contained in the material lying on the dumping plate. 75

4. In combination, a steam boiler, a centrally disposed combustion chamber extending beneath the boiler, a bridge wall through the center of said chamber, said wall having water boxes in the sides thereof 80 and openings between said boxes, and means for supplying air for combustion through said openings.

5. In combination, a steam boiler, a centrally disposed combustion chamber extending beneath the boiler, a bridge wall through the center of said chamber, said wall having openings in the sides thereof, and means for supplying air for combustion through said openings and for causing air 90 to play downward upon and across the top of the spent fuel adjacent to said wall. 85

6. In combination, a steam boiler, a centrally disposed combustion chamber extending beneath the boiler, stokers one at the 95 front and the other at the rear of the boiler said stokers having dumping plates, a bridge wall through the center of the chamber, said wall having openings in the sides thereof, and means for supplying air for combustion through said openings and for causing the air to blow over and impinge on the top of the partly spent coal lying on the dumping plates adjacent to said wall. 100

In testimony whereof I have hereunto 105 signed my name in the presence of two subscribing witnesses.

DAVID S. JACOBUS.
